CLAIM

The ornamental design for a golfing dice game as shown and described.

DESCRIPTION

FIG. 1 is a top front perspective view of one of the first dice of the golfing dice game;

FIG. 2 is a bottom rear perspective view thereof;

FIG. 3 is a plan view thereof;

FIG. 4 is a front view thereof;

FIG. 5 is a bottom view thereof;

FIG. 6 is a left side view thereof;

FIG. 7 is a right side view thereof;

FIG. 8 is a rear view thereof;

FIG. 9 is a top front perspective view of the second dice of the golfing dice game;

FIG. 10 is a bottom rear perspective view;

FIG. 11 is a plan view thereof;

FIG. 12 is a front view thereof;

FIG. 13 is a bottom view thereof;

FIG. 14 is a left side view thereof;

FIG. 15 is a right side view thereof;

FIG. 16 is a rear view thereof;

FIG. 17 is a top front perspective view of the third dice of the golfing dice game;

FIG. 18 is a bottom rear perspective view thereof;

FIG. 19 is a plan view thereof;

FIG. 20 is a front view thereof;

FIG. 21 is a bottom view thereof;

FIG. 22 is a left side view thereof;

FIG. 23 is a right side view thereof; and,

FIG. 24 is a rear view thereof.
